(57) **CLAIM**

The ornamental design for a thermostat mount, as shown and described.

DESCRIPTION

FIG. 1A is a perspective view of a thermostat mount showing the new design;

FIG. 1B is a front elevation view of the thermostat mount; and,

FIG. 1C is a front elevation view of the thermostat mount with a thermostat.

The thermostat mount includes a plain and unornamented top, bottom, left, right, and rear which are not shown; and The broken line showing of a thermostat in FIG. 1C is included for the purpose of illustrating environmental matter and forms no part of the claimed design.
